UNITED STATES PATENT OFFICE.

LOUIS E. FISCHER, OF ST. LOUIS, MISSOURI.

MONORAIL RAILWAY SYSTEM.

1,125,284.

Specification of Letters Patent. Patented Jan. 19, 1915.

Application filed January 24, 1914. Serial No. 814,163.

To all whom it may concern:

Be it known that I, LOUIS E. FISCHER, a citizen of the United States, residing at the city of St. Louis, in the State of Missouri, have invented certain new and useful Improvements in Monorail Railway Systems, of which the following is a specification.

My invention relates broadly to railway systems, and specifically to a class of railway systems commonly known as mono-rail systems.

Broadly, the purpose of my invention is to provide a practical mono-rail system, the same being rendered so by virtue of its economy, efficiency, strength, safety and simplicity.

More specifically, the purpose of my invention is to provide a mono-rail system wherein the track and the carriages are designed with special reference to each other for the purpose of securing a proper distribution of the carriage load over the track and its supporting members.

It is a further purpose of my invention to provide a mono-rail system in which adjacently disposed rails are adapted to supply support for the carriages and an electrical circuit for the motive force.

Further, it is an object of my invention to improve generally the track and carriage construction and the method of operation of such systems.

It will be understood by reference to the accompanying drawings that Figure 1 is a side elevation illustrating a portion of the track and a carriage. Fig. 2 is a section on line 1—1 of Fig. 1. Fig. 3 is a detail partly in section illustrating a portion of the track construction. Fig. 4 is a plan view of the construction shown in Fig. 1. Fig. 5 is a transverse vertical section of the construction shown in Fig. 1 showing two tracks.

Referring now to the drawings in detail, it will be understood that the numerals 1 and 2 indicate any suitable form of rails, that shown being the ordinary T type.

The numerals 4 indicate suitable supporting standards which are maintained rigidly upright in any suitable manner, and which support cross brackets 3. As shown in Fig. 5, it will thus be seen that these cross brackets 3 extend outwardly at both sides of the standards 4. The rails 1 and 2 are carried on the outer arms of the cross brackets 3, and inasmuch as these rails are designed to form the transmission circuit, they are

insulated from the cross brackets 3. Obviously, the cross brackets may be braced or reinforced in any desired manner. Either rail 1 or 2 constitutes a runway or track 60 along which the carriages may be operated. The supports for the rails 1 and 2, the same in this instance being the standards 4 and brackets 3, are disposed at uniform predetermined intervals, for a purpose herein-after indicated.

The carriage consists generally of a truck portion 8 and a body portion 7. The latter may have any characteristics which adapt it to passenger, freight, or other service, the essential feature being that it be narrow so as to have the minimum amount of overhang, and thus exert a minimum amount of leverage on the supports.

The truck is possessed of certain essential 75 characteristics both as to size and construction, as in these particulars it bears a specific relationship to the construction and dimensions of the track and track supports.

As illustrated, the truck is made up of the 80 sills 14' which are suitably stayed and connected together by proper braces and cross pieces 13 and 14. The construction is such as to provide a very stiff and rigid structure which will support the body without vertical strain or flexion of the truck.

As illustrated, the body may be supported from the truck by any suitable hangers 16 of proper formation to avoid the track supports and to provide attachment to the 90 truck. The truck is provided with a plurality of wheels 9 carried on the axles 11 suitably journaled on the truck, which wheels are adapted to ride on either of the rails 1 and 2, and are provided with flanges 95 12 on either side of the tread. The wheels are driven by a suitable transmission gearing 17, 18 and 19 which is actuated by the motor or motors 21.

In the form illustrated, I have shown the 100 truck equipped with five wheels, but, of course, other numbers of wheels may be employed. The length of the truck is such as to extend over three of the rail supports, illustrated as the standards 4 and the brackets 3, and the relative spacing of the wheels is such that when any one of the wheels is directly over one of the rail supports, one or more of the other wheels will be directly over other rail supports. This is the characteristic dimensional relationship of the 110 track structure and the carriage structure, and

its purpose is to secure equalization and distribution of the weight of the carriage over the rail supports and prevent heavy loading of the rails at points removed from the rail supports. The weight and load capacity of the body is so distributed as to equalize the load along the length of the truck, and, because the construction of the truck is possessed of much greater rigidity than are the rails, the weight of the carriage will always be supported on the wheels which are nearest to rail supports. Thereby, excessive loading of the rails at points removed from the rail supports where there would be danger of distortion or breaking of the rail, is prevented.

In the position illustrated in Fig. 1, it is obvious that one-fourth of the weight of the carriage will be supported on each of the first and fifth wheels, and one half by the third wheel, and the second and fourth wheels will be carrying no load and delivering no load to the rail. If the second wheel were over a support, the fourth wheel would be over another support, and each of said wheels would be carrying one-half the carriage load, and the first, third and fifth wheels would be delivering no load to the rails. When none of the wheels are over rail supports, the carriage load will be distributed among them inversely in ratio to their distances from the supports nearest them. Thus, if the wheels were all equidistant from rail supports, each wheel would be carrying one-fifth of the carriage load. As a result of this arrangement, it will be seen that the weight of the carriage will always be transmitted to the rails at points adjacent the rail supports rather than at points removed from the rail supports. As a result, the rails will never be broken or distorted by loading them at points where they are unable to carry the stresses. This construction in effect provides a movable truss which supports the car, and which is movable along over the supports. As this truss is moved along over the supports, the loading of the different wheels is constantly changing, due to the flexibility of the rail and the specific spacial relationship of the wheels and supports. The truss forms a movable cantilever having shifting fulcrum points, which fulcrum points are always on the wheels in closest proximity to the supports.

As stated above, the rails 1 and 2 are designed to form the circuit for the transmission of the current to run the motors 21. Hence, one of said rails will be of positive polarity, and the other of negative polarity. The current contact for the carriage motors may be made through the wheels 9 or through any other suitable means. Supported on the brackets 3, and insulated therefrom, are the roller blocks 22 and 23, in

each of which is mounted a metal roller 24. These rollers are designed to supply for the carriage a current contact of polarity opposite to that supplied by the rail upon which the carriage is supported. Hence, each of the blocks 23, which are designed to serve cars supported on rail 2, is electrically connected with rail 1, and each of blocks 22, which are designed to serve cars supported on rail 1, is electrically connected with rail 2.

Conveniently supported on the carriage are the brackets or arms 27 which support a shoe 28, which shoe is designed to make contact with the rollers 24 whereby to complete the shunt between rails 1 and 2 through the operating mechanism of the carriage. The arrangement of the shoe is such that it will always be in contact with one or more of the rollers 24, and hence the current supply to the carriage operating mechanism is constantly preserved. It will be understood that but slight modification of the circuit arrangements employed will be necessary for their adaptation to single track operation should such be desired, and it is obvious moreover that a suitable source of electrical energy may be carried by the car if desired.

Any suitable form of braking mechanism, such as a sort wherein the braking friction is applied to the wheels may be employed. Propeller 29 may form a part of the car equipment, which propeller may be actuated by a suitable power mechanism, either to drive the car or, by reverse rotation, to oppose its progress. The distribution of weight on the truck should be such as to slightly incline it inwardly toward the center of the brackets 3. Thereby, electrical contact of the shoe 28 with the rollers 24 is insured, and increased stability of suspension is obtained. This construction and arrangement is not only designed for very rapid travel, but also combines economy of construction with safety of service.

It is obvious that the principles of construction as hereinafter claimed are equally applicable to a modified suspended rail system in which two adjacent rails are used to support the carriages.

It will be obvious that many modifications of the system and construction shown and described will suggest themselves to those skilled in the art, and therefore, I do not desire my invention to be construed as limited to the embodiments herein shown, but intend that the appended claims be construed to comprehend all modifications within the spirit of the invention.

What I claim is:

1. In a mono-rail system, the combination of a rail supported by standards and a car supported from said rail at three or more points spaced apart longitudinally and movable along the same, the supports of

5 said car upon said rail having a definite specific relationship to the spacing between said standards, and the interval between the terminal supports being at least sufficient to include three of said standards.

10 2. In a railway system, in combination, an elevated rail, supports for said rail disposed at predetermined intervals, a carriage adapted for movement along said rail, said carriage including a plurality of wheels having relatively fixed axes and adapted to travel on the rail; the alternate wheels being spaced apart a distance equal to the spacing of the said rail supports.

15 3. In a mono-rail system, the combination of a rail having suitable supports, a truck supported upon said rail at three or more points and having a length equal to or exceeding the distance between any three 20 adjacent supports, and a car body secured to said truck, said truck being movable along said rail.

25 4. In a railway system, the combination of an elevated rail, supports for said rail disposed at predetermined intervals, a truck supported on and movable along said rail, a car supported on said truck, said truck including a plurality of wheels adapted to travel on said rail, said wheels being arranged in pairs spaced apart a distance equal to the spacing interval of said supports, certain wheels of certain of said pairs being disposed intermediate the wheels forming others of said pairs.

30 5. In a mono-rail system, the combination of a rail, supports for said rail disposed at predetermined intervals, a rigid truck portion, having three or more wheels adapted to coöperate with said rail disposed on said 40 truck portion in alinement, the spacing of certain of said wheels on said truck portion coinciding with the spacing of certain of said supports.

35 6. In a mono-rail system, the combination of a rail, supports for said rail disposed at intervals, a truck portion relatively stiffer than said rail, a car body supported from said truck portion, wheels disposed on said truck portion and adapted to coöperate with 50 said rail at three or more points longitudinally of the truck portion and over a plurality of said rail supports to afford a movable support for said body, and means for propelling the truck portion along the rail.

55 7. In a mono-rail system, the combination of a rail, supports for said rail disposed at intervals, a relatively rigid truck having a length at least equal to that of two of said intervals, wheels disposed in alinement on 60 said truck and adapted to coöperate with said rail to support the truck at three or more points longitudinally thereof, the longitudinal spacing of said wheels being such as to enable certain of said wheels to register simultaneously with certain of said sup-

ports, and a body suitably supported from said truck.

8. In a mono-rail system, the combination of a rail, supports for said rail disposed at intervals, a relatively rigid truck having a length at least equal to that of two of said intervals, wheels disposed longitudinally on said truck and adapted to coöperate with said rail at three or more points longitudinally thereof, the longitudinal spacing of certain of said wheels exceeding the maximum spacing of juxtaposed supports, and a body supported from said truck and adapted to balance the same on said rail.

10 9. In a mono-rail system, a flexible rail, supports for said rail disposed at intervals, an inflexible truck having a length at least equal to that of two of said intervals, wheels disposed on said truck and adapted to coöperate with said rail at three or more points longitudinally thereof, the spacing between certain of said wheels exceeding the maximum spacing between juxtaposed supports, and means for balancing the truck on the rail.

15 10. In a mono-rail system, a flexible rail, supports therefor disposed at intervals, a relatively inflexible truck having a length at least equal to that of two of said intervals, end wheels disposed on said truck and adapted to coöperate with said rail, wheels disposed on said truck intermediate said end wheels and adapted to coöperate with said rail, said wheels being fixed against vertical movement relative to said truck, and means for balancing the truck on the rail.

11 11. In a railway system, an elevated rail, supports for said rail disposed at predetermined intervals, a carriage adapted for movement along said rail, said carriage including a truck and a body portion supported from said truck having a length sufficient to span at least two of said intervals, said truck being provided with end wheels and a medial wheel intermediate said end wheels, said truck being further provided with wheels intermediate the medial and the end wheels, all of said wheels being adapted to coöperate with said rail.

12 12. In a railway system, an elevated rail, supports therefor disposed at intervals, a structure for supporting wheels having a length sufficient to span at least two of said intervals, wheels journaled on said structure in journals fixed against relative spacial movement, and means for driving certain of said wheels.

13 13. In a system of the class described, a plurality of supports spaced apart from one another by predetermined intervals, a truss member having three or more points of suspension movable onto said supports consecutively and adapted to span at least two of said intervals, means supported on said supports for guiding said truss member on and

between said supports, means for propelling said truss member, and a car supported by said truss member.

14. In a system of the class described, a plurality of supports disposed at predetermined intervals, a movable truss member adapted to be supported thereby and having a length sufficient to span at least two of said intervals, means supported by said supports and adapted to guide said truss member thereon and therebetween, means for propelling said truss member, said truss member including three or more wheels adapted to coöperate with said supports to form fulcrum points for said truss member.

15. In a system of the class described, a plurality of supports disposed at a predetermined interval, a truss member adapted to be supported thereon at three or more points longitudinally spaced apart and having a length sufficient to span at least two of said intervals, a car body supported by said truss member, and means for moving said truss member along said supports consecutively. 20

In testimony whereof I affix my signature 25 in presence of two witnesses.

LOUIS E. FISCHER.
